UNITED STATES PATENT OFFICE.

ROMAN F. POLSKI, OF ST. PAUL, MINNESOTA.

PADDED COVER FOR IRONING BOARDS.

Application filed June 24, 1925. Serial No. 39,244.

It is my object to provide an improved cover and pad therefor, adapted to be quickly and easily attached to and detached from the top of an ironing board of common type.

5 Heretofore, it has been common practice to secure the covers and pads to ironing boards by the use of nails, tacks or similar fastening means, and much time and labor has been expended in so attaching the covers, 10 either after removal for washing or to replace a worn cover by a new one. In my improved cover, all such fastening means are done away with, and it is only necessary to extend the cover by stretching to a limited 15 extent, and then to draw the margins thereof downward over the edges of the ironing board top.

In the accompanying drawings, forming 20 part of this specification, Figure 1 is a perspective view of the cover showing the bottom thereof, detached from the board top; Fig. 2 is a transverse section through the board top with the cover and pad in place thereon; Fig. 3 is a fragmentary, perspective 25 view of the margin of the cover and Fig. 4 is a perspective view of the board assembled and with one corner of the cover raised in position for final stretching into place on the top.

30 As illustrated, I provide an ironing board top 5 having the usual tapered or converging end 6, a squared end 7 extending at right angles to the longitudinal side edges and rounded corners at the junctions of the ends 35 and sides of the board. My improved cover 8 is formed with an end 9 adapted to conform to the end 6 of the board, the opposite extremity of the cover being formed to fit the end 7 of the board. To form flanges 10 40 around the margin of the cover 7, said margin is gathered where it is to fit the corners or convex portions of the top 5, as indicated at 11 in the drawings.

An endless tape 12 is sewed to the normally lower edge of the flange 10. This tape is made of a material having less elas-

ticity than the fabric of the cover 8, and is of smaller perimeter than the board 5, so that said tape normally lies within the outer margin of said board when the cover is in 50 position thereon. The pad 13, which is adapted to be placed beneath the cover 8, is constructed of suitable thick fabric, or may be made of a number of thicknesses of cloth bound at their edges one to the other, but is 55 otherwise formed like the cover 8 with marginal tape and gathered portions.

To mount the cover and pad on the top 5, the end 6 of said top is inserted in the tapered end 9 of the cover and corresponding end of the pad, so that said cover and pad cap the end of the board. Now the opposite end of the cover and pad may be forcibly stretched over the squared end 7 of the top 5, so that the tape 12 is carried downward beneath the board. Now, when released, the tape maintains the fabric of the cover and pad tightly upon the top 5. To remove the cover or pad, it is only necessary to grasp the tape 12 near one of the gathered 70 portions 11 and to stretch the fabric sufficiently to permit the tape to be carried upward past the edge of the top 5.

Having described my invention what I claim as new and desire to protect by Letters Patent is:—

The combination with an ironing board top, of a cover constructed of a somewhat elastic fabric and formed with a margin constituting flanges adapted to extend downward about the edges of said top, and a looped tape, of material having less elasticity than said cover, secured to said margin and arranged to be drawn over said top while stretching the fabric of said cover, said tape being shorter than the perimeter of said top and constituting a permanently attached binding strip extending entirely around the margin of the cover.

In testimony whereof, I have hereunto signed my name to this specification.

ROMAN F. POLSKI.
